UNITED STATES PATENT OFFICE.

AXEL S. CARLSON, OF LOS ANGELES, CALIFORNIA.

WATER-HEATER.

1,199,450.

Specification of Letters Patent. Patented Sept. 26, 1916.

Application filed July 12, 1915. Serial No. 39,230.

To all whom it may concern:

Be it known that I, AXEL S. CARLSON, a citizen of the United States, residing at Los Angeles, in the county of Los Angeles and State of California, have invented new and useful Improvements in Water-Heaters, of which the following is a specification:

My invention relates to water heaters and more particularly to that class of heaters used in heating water for domestic purposes.

It is an object of my invention to provide a water-heating device that may be applied to the ordinary gas or oil stove without the need of alterations of the parts of the stove in order to make the attachment.

It is the further object of my invention to provide a water-heating device that will heat water and at the same time make it possible to utilize the flame for the heating of utensils which may be placed on the grate above the flame; the water-heating device being connected with the ordinary storage or circulating boiler in use for domestic purposes. Thus it may be seen that water may be heated and at the same time a meal may be in the cooking process with the utilization of but a single burner. In actual practice it has been found that a tank of thirty gallons capacity was heated to a high temperature during the preparation of a single meal.

It is also an object of my invention to so arrange the heating coil within my device that the maximum heat will be absorbed from the flame and at the same time adequate space be afforded for the passage of the flame to the grate above said coil.

Another object of my invention is to provide a device that is cheap and simple in construction, and that may be easily adapted to any make of stove without the necessity of special fittings for each make of stove.

Heretofore it has been customary, when heating water for domestic purposes, to provide a tank and a special heating device for supplying heat thereto. With my device such an outfit is unnecessary.

My device is illustrated in the accompanying drawings in which:

Figure 1 is a section in side elevation showing the application of the preferred form of my invention to the burner of an ordinary gas stove. Fig. 2 is a plan view of my device as applied and illustrating the arrangement of the heating coil. Fig. 3 is a plan view of one complete convolution of

the heating coil. Fig. 4 is a section on the line 4—4 of Fig. 3. Fig. 5 is a section in side elevation of a modification of my invention. Fig. 6 is a plan view of Fig. 5.

More specifically, 10 is the burner of a gas stove of ordinary construction supplied with fuel by the supply pipe 11 upon which is mounted, by brackets 12 and 13 the annular outer wall 14 of the heat chamber 15, formed upon the inner periphery of which is the internal flange 16 to which are attached the radial grate bars 17 having inwardly extending portions 18 for the support of utensils placed over the flame, and outwardly extending portions 19 provided with lugs 20 which rest upon the stove top 21. Secured to the lower portion of the inner periphery of the wall of the heat chamber is an annular channel member 22, the inner wall thereof being so positioned that there will be a space 24 between said wall and the burner to afford circulation of air.

The heating coil consists of a pipe 23 which is led through the channel member 22 and is arranged in uniform convolutions 80 around the inner face of wall 14 and above the annular channel member 22. The uppermost stratum 26 of the heating coil is adjacent the inturned flange 16 of the heat chamber and is so arranged that the pipe 85 forms a spiral which, upon reaching the center, reverses and again passes in the path of the former spiral to within the outer coil of pipe. Particular attention is directed to the sectional shape of this pipe, it being oval with the major axis extending vertically so that the maximum amount of heating coil can be crowded into the upper strata 26 without obstructing the flame in its passage from the burner to the grate. After the pipe has reached the outer coil it passes through opening 27 in the outer wall 14 and connects with pipe 28 by means of union 29 to a storage or circulating tank of common construction from which source the water returns through pipe 25.

As shown in Fig. 1, the heating coil advances in a uniform helix but in Figs. 3 and 4 the coil is shown as entering the heating chamber at 30 making one revolution 31 and upon coming to the point of entrance is bent outwardly at 32 and makes another revolution 33 concentric with and on the outside of revolution 31; upon reaching point 34 it passes across the bend 32 and bends up

wardly as shown at 35 and continues in the same manner of the two last described convolutions. It will be seen that this arrangement causes two complete convolutions of the pipe to lie in the same horizontal plane and affords the opportunity for arranging a greater length of pipe within a given area. The modification of my invention as disclosed in Figs. 5 and 6 necessitates the use of the same burner and grate arrangement but the circulatory system of the water is in some respects different, the heat chamber 36 consisting of an annular outer wall and a similar inner wall 37 spaced from each other and closed by top member 38 and bottom member 39. Secured to the inner surface of the inner wall is an annular channel member 40 having its inner wall 41 spaced a distance 42 from the burner 10. Secured by screws 43 to the upper portion of heat chamber 36 is an annular cap 38 upon which are secured the radial grate bars 17 whose formation and function is the same as that shown in Fig. 1.

25 In the modified form of my invention the water passes from a tank to the pipe 44 which is secured within an elbow 45 threaded at one end 46 and engaging complementary threads 47 within the outer wall of the heat chamber. The water then fills the annular space 48 and passes out through the pipe 49 into the spirally arranged coil 49' after passing through which it returns to the tank through the pipe 50. Thus it is seen that in the modified form a large quantity of water will be in position to absorb the heat from the burner without the necessity of using the long length of heating coil as used in my preferred form.

40 In the operation of my device the gas in the burner is ignited, the flame from which is supplied with air passing up through the annular opening 24 to provide proper combustion of the gas. The flame then passes up through the heat chamber between the convolutions of the upper strata 26 of the heating-coil and out to the grate member, The horizontally disposed annular ring member 16 in conjunction with the side wall 50 forms a pocket 51 in which a portion of the heat is trapped and affords the opportunity for the heating coil to absorb said heat; the annular channel ring member 22 protecting the heat coils from the direct draft of cool air which is inclined to be drawn through the heating chamber and makes a more efficient trap for the heat caught by the ring member 16. Thus it may be seen that no heat is allowed to be wasted in this device but is either absorbed by the heating coil or applied to any utensil placed upon the grate.

55 The operation of the device is the same in the modified form as in the preferred form.

60 65 The heat, however, is trapped in a much

smaller space 52 than that used in the preferred form. Otherwise the operation of the two devices is identical.

What I claim is:

1. In a water heater the combination of a burner, a heat chamber surrounding said burner having an outlet and formed with an annular baffle plate at its upper edge and a detachable obstructor plate at its lower end through which the burner extends, a water conduit extending the length of the heat chamber throughout the surface of the inner wall thereof and partially obstructing the outlet to the heat chamber, and a grate positioned over said outlet. 8
2. In a water heater, the combination of a burner, a wall encircling the burner and extending above and below the upper face thereof, a conduit adjacent the inner face of said wall and connecting with a source of water supply at its lower end, a tubular conduit arranged in a coil above the burner and extending across a space at the upper end of the wall, said coil connecting at one end with the first named conduit and having its other end leading to a point of discharge, an inwardly extending flange on said wall projecting over the outer portions of said coil, a removable inwardly extending flange on the lower end of said wall projecting toward said burner with its inner edge spaced therefrom, and a grate positioned over the coil. 85
3. In a water heater the combination of a burner, a wall encircling the burner and extending above and below the upper face thereof, a conduit adjacent the inner face of said wall and connecting with a source of water supply at its lower end, a tubular conduit arranged in a coil above the burner 100 and extending across a space at the upper end of the wall, said coil connecting at one end with the first named conduit and having its other end leading to a point of discharge, an inwardly extending flange on said wall projecting over the outer portions of said coil, a demountable inwardly extending flange on the lower end of said wall projecting toward said burner with its inner edge spaced therefrom, and a grate positioned over the coil. 105
4. A combination of a burner, an annular wall encircling the burner and extending above and below the upper surface thereof having an inwardly extending flange on its upper edge and a detachable inwardly extending flange on its lower edge, said last named flange terminating in spaced relation to the burner, a tubular conduit arranged in a coil and extending across the opening formed at the upper end of the wall, a tubular coil formed in continuation of the first named coil extending downwardly in a se- 115 120 125 130

- ries of connected annular coils arranged adjacent to the inner face of the wall and connecting with a source of water supply at its lower end, and a grate positioned across the 5 opening at the upper end of the wall.
5. In a combined stove and water heater, the combination of a burner, a wall encircling the burner and spaced therefrom forming a heat chamber, a removable inwardly extending flange on the lower end 10 of said wall arranged below the upper surface of the burner, an inwardly projecting flange on the upper end of said wall, arranged above the upper surface of the 15 burner, a grate positioned above the opening formed at the upper end of said wall, and a water heating coil arranged adjacent the inner face of the wall encircling the burner, having its lower end connected with 20 a source of water supply and its upper end leading to the point of discharge.
6. In a water heater, the combination of a burner, a wall encircling the burner and spaced therefrom, and projecting the e-
- above, an inturned overhanging flange on the upper end of said wall, grate bars carried by said flange, an inturned flange on the lower portion of the wall having its inner annular edge encircling the burner and spaced therefrom, and a spiral conduit 25 arranged adjacent the inner face of the wall between the upper and lower flanges.
7. In a water heater, the combination of a burner, a wall encircling the burner and spaced therefrom, and projecting there- 30 above, an inturned overhanging flange on the upper end of said wall, grate bars carried by said flange, a removable inturned flange on the lower portion of the wall having its inner annular edge encircling the 35 burner and spaced therefrom, and a spiral conduit arranged adjacent the inner face of the wall between the upper and lower flanges.

In testimony whereof I have signed my name to this specification.

AXEL S. CARLSON.
